UNITED STATES PATENT OFFICE.

WILBUR H. WADSWORTH, OF WATERTOWN, NEW YORK.

SNOW PLOW.

Application filed March 2, 1927. Serial No. 172,068.

This invention relates to improvements in snow plows, designed especially for clearing snow from highways, and has for its particular object to provide a horse-drawn snow remover, which is mounted upon bob-sleighs or runners, and is arranged to disperse the snow towards the opposite sides of a roadway simultaneously. A further object is to provide an elongated frame, which is pivotally supported near its opposite ends by front and rear bobs. A further object is to provide similar right and left hand plows, which are disposed at the opposite sides of the frame, the said plows being secured to the frame by chains or other flexible means, whereby the plows may float and accommodate themselves to strains and inequalities in the roadway; each plow comprising a mold-board, which is arranged at an oblique angle to the linear dimension of the frame, the spread of the said mold-boards, being such as to plow or clear a path sufficiently broad to enable two vehicles to pass each other. A further object is to provide means for adjusting the opposing plows, i. e. to raise and lower them for enabling the machine to be moved freely from place to place, as well as to pass over rocks and other obstructions that rise above the normal grade of the roadway. And a further object is to generally improve and simplify the construction and operation of snow removers of the class.

I attain these objects by the means set forth in the detailed description which follows, and as illustrated by the accompanying drawings, in which—

Figure 1 is a top plan view of the complete machine. Fig. 2 is a vertical cross-section taken on line 2—2 of Fig. 1. Fig. 3 is a similar section taken on line 3—3 of Fig. 1. Fig. 4 is a detached plan view of one of the floating plows. Fig. 5 is a broken side elevation, taken in the direction of the arrow in Fig. 1, the left-hand plow being removed; and showing the right-hand plow elevated. Fig. 6 is a full side elevation of the machine, showing the plows in the lowest position. Fig. 7 is a top plan view of the front bob to which the auxiliary scraper is applied. And Fig. 8 is an end view of the scraper.

In the drawings, 2 and 3 represent respectively the front and rear bobs, the runners

of which are permanently connected by 55 means of cross-beams 2'—3' upon which are mounted bolsters 2"—3", the latter being pivoted to the beams in the usual manner, by pins α . The runners of the bob 2 pivotally support a tongue 2^b, the rear end thereof being fitted with a cross-bar 2^c, whose opposite ends are provided with gudgeons that journal in loop-bearings 2^d, carried by the runners. The bar 2^c is provided with a rearwardly extending loop 2^e, to which are attached a series of flexible draft rods or chains, as 4—4', that connect respectively with the right and left hand plows.

5—5' represent elongated members of the frame, whose front and rear ends are respectively supported by the bolsters 2"—3", and therefore tie the bobs 2 and 3 together. The members 5—5' are preferably disposed parallel and spaced from each other, and the medial portions of said members are stiffened by means of similar reinforcing timbers or parts, as 5", which are secured by bolts 5^b. Midway between the bobs, upright posts 6—6' are rigidly secured to the outer edges of the frame members 5—5' by bolts 6", and the said posts are respectively tied together and spaced near their top ends, by cross-bars 6^c. The posts 6' are taller than the posts 6 and are fitted with notched plates 6^d, by which certain adjustments of the 85 plows may be maintained.

7—7' represent respectively the right and left hand plows, which are similar in construction and operation. Each plow consists of a mold-board, as 8, preferably made 90 of wood, and each mold-board preferably comprises two sections, as 8'—8", which are joined end to end and rigidly held in place by cleats 8^b, said parts being secured by bolts, as shown. The front surfaces of the mold-boards are faced near their lower edges with sheet metal, as 8"—8^a, the strips 8^c being concave and comprising the cutting or scraping edges that travel frictionally over the surface of the roadway. The mold-boards are 95 preferably disposed at an angle approximating 45° to the longitudinal dimension of the machine, and said boards preferably incline upwardly and rearwardly to facilitate the free movement of the snow. The mold-boards 8—8' are supported by longitudinal members 9—9' which correspond to and 100 perform the same function as the "land

sides" of the ordinary farming plows, to which the mold-boards are secured by bolts 9^a, and also by a series of angular braces 9^b—9^c. The members 9 are disposed outside of and loosely engage the lower end portions of the posts 6—6' and are therefore free to move or float laterally, as well as vertically, during the plowing operations. The members 9—9' normally rest upon the roadway during the plowing. The plows are drawn forwardly solely by the rods or chains 4—4', the rear ends of which are respectively connected to the plows, by means of loops 7^a, the latter being secured to the mold-boards and the members 9 (see Figs. 1, 2 and 4). The rear ends of the members 9 are flexibly supported by chains 9^d, which are suspended from the rear ends of the timbers 5^a. The plows 7—7' may be lifted clear of the roadway independently, by means of levers 10—10', the latter being pivoted to the shorter posts, and their forward ends are connected to the members 9—9', by chains 10^c. Each lever 10 is fitted with a latch 10^d, which is arranged to engage the notches in the plates 6^a for holding the levers in various adjusted positions. In Fig. 5 the levers 10 are positioned horizontally for raising the plows clear of the roadway, as A. In Fig. 6 the levers are swung upwardly, which effects the lowering of the plows to the plowing position. It will be understood that when the machine is moving forward the angularity of the mold-boards 8—8' tends to force and hold the plows inwardly against the posts 6—6', and that the relatively short chains 9^d and 10^c allow the plows to swing outwardly laterally sufficiently to prevent cramping and binding of the parts. 6^x represents guy-chains for connecting the tops of the posts 6' to the rear top-portions of the mold boards 8, to prevent undue spreading and straining of said portions, and for supplementing the flexible ties 9^e—10^e. The plows 7—7' are normally spaced the breadth of the frame and therefore may only remove the snow at either side of the center portion of the roadway. To level or remove the more closely packed snow that lies between the paths of the two plows, I provide an auxiliary scraper or part consisting of a concave strip of sheet metal, as 12, which is arranged to be disposed angularly across the runners of the front bob 2, as shown in Figs. 7 and 8. The scraper 12 is provided with a forked reach 12', whose free end is formed with a hook 12^a, which engages the loop 2^e carried by the tongue, by which the scrape is drawn forwardly. The scraper is held in its angular position by rods or chains 12^b of different lengths, which may be anchored to a hook 12^c carried by the beam 2', the scraper 12 may be operated conjointly with the two plows as indicated in Fig. 1. The scraper

may be operated alone with the front bob, as shown in Fig. 7, or when the plows are in the inoperative position, shown in Fig. 5.

Having thus described my invention, what I claim, is—

1. In a snow remover, the combination with front and rear bob sleighs and a frame pivoted at its opposite ends to the bobs, of similar plows disposed at the opposite sides of the frame between said bobs, posts arranged in pairs secured to the opposite sides of said frame against which the "land sides" of the plows bear, chains connecting the rear ends of the "land sides" to the frame, levers for raising and lowering the plows relatively to the frame said levers being pivoted to the forward pair of posts, and chains connecting the forward ends of the levers to the forward portions of the plows. 70 75 80

2. In a horse drawn snow remover, front and rear bob sleighs, an elongated frame connecting and spacing said bobs, similar plows disposed at the opposite sides of the frame, the "land sides" of the plows being arranged parallel to the frame and loosely engaging depending portions of the frame, flexible means for connecting the rear ends of the "land sides" to the frame, levers for raising and lowering the plows above the roadway pivoted to the frame, flexible means connecting said levers with the forward ends of the "land sides," and flexible means for separately connecting the forward ends of the plows to the front bob, for propelling said plows. 85 90 95 100

3. In a snow remover for highways, the combination with front and rear bob sleighs, of a frame supported by and spacing said bobs, posts arranged in pairs supported by the frame between the bobs, similar plows comprising mold-boards and land-sides disposed at the opposite sides of the frame and outside of said posts, the "land sides" of the plows arranged to frictionally engage the lower ends of the posts, flexible means connecting the rear ends of the "land sides" to the frame, levers disposed parallel to the frame outside of the posts for raising the plows above the roadway, said levers being pivoted to the forward pair of posts, locking means carried by the rearmost posts and by said levers for maintaining the adjustments of the plows, flexible means connecting the forward ends of the levers to the corresponding portions of the "land sides," draft means connecting the plows to the forward bob, and flexible means for connecting the rearmost posts with the mold-boards of the plow. 105 110 115 120 125

4. In a snow remover for highways, front and rear bob sleighs, an elongated frame pivoted at its opposite ends to said bobs, posts arranged in pairs secured to the opposite outer sides of the frame between the bobs, triangular shaped plows disposed at the opposite sides of the frame, one arm of 130

each plow loosely engaging the lower ends of the corresponding posts, the other arms comprising mold-boards arranged to disperse the snow laterally from the frame, means connecting the forward ends of the plows to the forward bobs for propelling the plows, means for flexibly connecting the rear portions of the plows to the corresponding sides of the frame whereby the plows may move

freely independently of the frame, levers for raising the plows clear of the roadway, flexible means connecting said levers to the forward portion of the plows, and means for locking said levers in various adjusted positions.

In testimony whereof I affix my signature.

WILBUR H. WADSWORTH.
